UNITED STATES PATENT OFFICE

91,065

DESIGN FOR A TILT-FRONT HAMPER

Lurelle Guild, Darien, Conn., assignor to C. F. Church Mfg. Co., Holyoke, Mass., a corporation of Massachusetts

Application August 26, 1933. Serial No. 49,117

Term of patent 7 years

To all whom it may concern:

Be it known that I, LURELLE GUILD, a citizen of the United States, residing at Darien, in the county of Fairfield and State of Connecticut, have invented a new, original, and ornamental Design for a Tilt-Front Hamper, of which the following is a specification, reference being had to the accompanying drawing, forming part thereof.

Fig. 1 is a perspective view of my new design showing the hamper open; and

Fig. 2 is a perspective view similar to Fig. 1 showing the hamper closed.

I claim:

The ornamental design for a tilt-front hamper substantially as shown.

LURELLE GUILD.
